PROCESS OF PRODUCING CHLORATES AND CHLORITES OF DIFFERENT METALS

Clifford A. Hampel, Harvey, Ill., assignor to Cardox Corporation, Chicago, Ill., a corporation of Illinois

Application February 13, 1946, Serial No. 647,404

15 Claims. (Cl. 23—85)

1

This invention relates to a new process for the production of a chlorate and a chlorite.

It has been known heretofore that a chlorate and a chlorite of the same metal can be produced by the absorption of chlorine dioxide by an alkali compound of that metal. For example, if potassium chlorate and potassium chlorite are to be produced, potassium hydroxide has been employed as the alkali compound. The equation which illustrates this reaction is:

This prior known process has possessed several inherent disadvantages. For example, there may be numerous commercial and economic reasons why a particular manufacturer may want to produce for use or sale a chlorate of one metal and a chlorite of a different metal. To accomplish this desired result with the prior known process, it is necessary to carry out this process twice, using one metal alkali to produce the desired chlorate of that metal in one process operation and using a different metal alkali in the second process operation to produce the desired chlorite of the different metal. Therefore, four products are formed, although only two really are desired.

Another inherent disadvantage of the prior known process is that it is extremely difficult and often impossible to effect by practical commercial means the separation of the chlorate and the chlorite of the same metal. Consequently, after practising two different processes to obtain four products, only two of which are really desired, the manufacturer has been confronted with the additional problem of separating out the two desired products.

It is the primary object of this invention to provide a single process for the production of a chlorate of one metal and a chlorite of a different metal in which the chlorate and the chlorite can be selected in accordance with the particular commercial needs of a given manufacturer.

It is a further important object of this invention to provide a single process by means of which a desired chlorate and a desired chlorite can be produced, and in which the chlorate and the chlorite thus produced can be obtained by the use of less expensive materials than the corresponding metal base or bases.

A further primary object of this invention is to provide a single process by means of which a chlorate of one metal and a chlorite of a different metal are produced simultaneously and

which are readily separable by known commercial facilities.

A specific object of this invention is to provide a single method of producing a chlorate of one metal and a chlorite of a different metal, in which one or the other is considerably less soluble in the same system, thus making them more readily separable.

Another specific object of the invention is to provide a single process for producing a chlorate of one metal and a chlorite of a different metal, in which substantially all of a particular cation introduced into the system, and which is capable of forming the chlorate, is utilized in the production of the chlorate while the chlorite of a different metal is formed.

Another specific object of the invention is to provide a single process for the production of a chlorate on one metal and a chlorite of a different metal, by which certain raw materials can be employed for producing one of the desired products which are different from and less expensive than the base, which is normally employed to produce that product. The use of less expensive materials is made possible by employing the salt of the metal of the desired chlorate or chlorite, which salt is less expensive than the corresponding base, and the base of the metal of the chlorate or chlorite desired, whereby the thus combined salt and base materials will introduce only a foreign anion, which anion will form a salt with the base cation which is less soluble in the system than the chlorate and/or chlorite produced.

Other objects and advantages of the invention will become apparent during the course of the following description.

As has been pointed out above, and as is specifically illustrated in Equation *a*, it has been known that the chlorate and chlorite of a given metal can be produced by reacting chlorine dioxide with the base of that metal. In accordance with the present invention, substantially stoichiometrically equivalent quantities of a chlorate and a chlorite of different metals are produced.

For example, a chlorate of a metal selected from the class consisting of potassium, sodium, lithium, barium, calcium, strontium, or magnesium can be produced in a single process simultaneously with the production of a chlorite of a different metal selected from the class consisting of potassium, sodium, lithium, barium, calcium, strontium, or magnesium.

By way of example, if it is desired to produce potassium chlorate simultaneously with sodium

chlorite, this reaction is illustrated by the following equation:

It will be noted that in this typical reaction substantially all of the potassium appears as the chlorate and substantially all of the sodium appears as the chlorite. Also, this potassium chlorate and sodium chlorite which are produced can be readily separated by taking advantage of their mutually different solubilities in the resultant system. This same condition holds true with the production of any one of the chlorates of the metals enumerated above, simultaneously with the chlorite of a different one of the metals enumerated above. The chlorine dioxide may be absorbed in an aqueous mixture of stoichiometric equivalents of two different hydroxides of the alkali, the alkaline earth metals and magnesium, such as those mentioned above, until substantial neutralization is effected. If desired, the chlorine dioxide may be passed first into one of the selected alkalis alone until substantially complete neutralization is effected. Then the other alkali is added and the chlorine dioxide is continued to be delivered until neutralization again occurs. Instead of employing the hydroxides of the metals of the chlorate and chlorite to be formed as the bases involved in Equation *b*, another compound such as the oxide or carbonate of one of these metals may be employed. The term "hydroxide" as used in the claims embraces the introduction of oxides of the named metals into the system since oxides will inherently form the hydroxides of the named metals in an aqueous medium.

Instead of employing the alkali compounds such as the oxides, hydroxides or carbonates as the sources of the metals of both the chlorate and chlorite to be formed, the discovery has been made that it is possible to employ a salt as the source of the metal of either the chlorate or the chlorite being produced. An example of this is given in the following equation:

In this last equation, it will be noted that both stoichiometric equivalents of the alkali required for the production of the resultant chlorate and chlorite from chlorine dioxide are furnished by the single base. Additionally, only one of the two stoichiometric equivalents of the metal introduced as the base is used in the formation of the chlorate or chlorite of that metal, while the other stoichiometric equivalent of the metal of the base is used to precipitate the foreign anion introduced as the salt of the other metal, said precipitated salt being less soluble than the chlorate and/or chlorite formed and, therefore, being readily separable from the system. Also, the chlorate and chlorite thus produced are readily separable because of their mutually different solubilities.

From the peculiarities noted above in connection with the process exemplified by Equation *c*, it will be appreciated that the single base and the salt that are employed must be so selected that the cation of the base, when combined with the anion of the salt, forms a third compound that is of relatively different solubility than the specific chlorate and chlorite selected for production, under the conditions existing in this system. Additionally, when certain chlorates and chlorites are desired to be produced simultaneously,

this process exemplified by Equation *c* offers marked advantages over that set forth in Equation *b*. For example, when it is desired to produce potassium chlorate and calcium chlorite, the employment of calcium hydroxide and potassium sulfate would entail about one-fourth the present raw material cost of employing corresponding (stoichiometrically equivalent) quantities of potassium hydroxide and calcium hydroxide.

To further exemplify this invention, it has been discovered that a chlorate of one metal and a chlorite of a different metal can be produced by employing salts of the metals of both the chlorate and the chlorite desired, in combination with an alkali of a still different metal. This results in the production of a chlorate of one metal, a chlorite of another metal, and a third compound resulting from the combination of the cation of the alkali used and the anion of the salts used. This process can be exemplified by the following equation:

In this last equation, it will be noted that both stoichiometric equivalents of the alkali required for the production of the resultant chlorate and chlorite from chlorine dioxide are furnished by the single base, while the cation of this alkali is not associated with either the chlorate or the chlorite, but substantially all becomes associated with the anion introduced as the salts of the other two metals. Although the salts of the two metals, which are introduced and subsequently appear as the chlorate and chlorite in the equation presented above, have a common sulfate ion, it is possible to use salts of two different acids, in which case the metal of the alkali introduced will be associated with these two different anions.

It further will be noted that in this Equation *d*, the single base and the salts that are employed must be so selected that the cation of the base, when combined with the anions of the salts, forms a third compound that is of relatively different solubility than the chlorate and the chlorite selected for production, under the conditions existing in this system. Additionally, when certain chlorates and chlorites are desired to be produced simultaneously, the process exemplified by Equation *d* offers marked advantages over that exemplified by Equation *b*. For example, when it is desired to produce potassium chlorate and sodium chlorite, the employment of calcium hydroxide, potassium sulfate and sodium sulfate would entail about one-half the present raw material cost of employing corresponding (stoichiometrically equivalent) quantities of potassium hydroxide and sodium hydroxide.

It is believed to be desirable at this point to further emphasize the economies that can be effected by means of the processes exemplified by Equations *c* and *d*, and the flexibilities of procedure that are made possible by these two methods of operation. For example, if the metal of either the desired chlorate or chlorite is available as a sufficiently inexpensive base, that base can be employed in combination with a metal salt of the other metal involved for producing a chlorate or chlorite of one of these metals and the chlorite or chlorate of the other one of these metals. On the other hand, when a chlorate of one metal and a chlorite of another metal are desired, and a base of neither one of these metals is available at a sufficiently low cost, it is possible by practising the process represented by Equation

d to use a low cost third metal base with a low priced salt of the metal of each of the chlorate and the chlorite desired, in order to produce the chlorate and the chlorite of the two metals. Also, each one of the three modes of operation exemplified by Equations *b*, *c* and *d* offers a process whereby the chlorate of one metal and the chlorite of a different metal may be produced simultaneously with substantially complete utilization, as a chlorate, of all of the metal whose chlorate is desired and substantially complete utilization, as the chlorite, of all of the other metal whose chlorite is desired.

It has been pointed out above that in practising the process exemplified by Equation *c*, the anion of the salt chosen to supply the one metal must be such that in combination with the metal of the base chosen, a salt is formed whose solubility is different from the metal chlorate and the metal chlorite formed, to facilitate their separation by commercially available facilities. Also, in practising the process exemplified by Equation *d*, these general considerations referred to in connection with Equation *c* apply with reference to the anions of the two salts and the metal of the base.

It is of advantage that the third compound formed as described above in the reactions exemplified by Equations *c* and *d* be appreciably less soluble than either the chlorate and/or the chlorite produced. In this case, it can be substantially completely removed from the system to leave remaining only a mixture of the chlorate and chlorite. For example, if an alkali of one of the alkaline earth metals is employed as the base, suitable metal salts, used to introduce the metal or metals of the chlorate and chlorite, would include such salts as the sulfate, fluoride, phosphate, silicate, fluorosilicate and arsenate. Further, if a magnesium alkali is employed as the source of the base, suitable metal salts, used to introduce the metal or metals of the chlorate and chlorite, would include such salts as the fluoride, phosphate, silicate and arsenate.

The use of salts which decompose chlorites under the conditions of the process is to be avoided. For example, if potassium dihydrogen phosphate were added to a substantially neutral solution containing calcium chlorite, the resulting acidic solution would decompose the calcium chlorite. If, however, sufficient alkaline material were present or added to neutralize the acid salt, the acid salt could be used to introduce the phosphate ion.

Although it has been pointed out above that the third compound formed under the reactions exemplified by Equations *c* and *d* should be such that its solubility differs from the solubility of the chlorate and chlorite to facilitate ready separation of this third compound from the other components of the system, it is recognized that a commercially valuable chlorate or chlorite product would be produced, if the aforementioned third compound were left associated with either the chlorate or the chlorite. When this is the case, the metal of the base and the anion of the salt or salts selected need only be such that the third compound is selectively soluble with reference to only one of the major products, namely, the chlorate or the chlorite.

To exemplify the above noted innovation to the processes represented by Equations *c* and *d*, it is possible to use alkali metal bases as well as the alkali earth metal and magnesium bases, and also to use such additional salts as the chlorides.

and nitrates to introduce the metals of the chlorate and the chlorite. An example illustrating this mode of operation is that of the production of a mixture of potassium chlorate, sodium chlorite and sodium sulfate. This mixture can be obtained by the reaction shown in the following equations:

In the procedure shown by Equation *e*, the potassium chlorate content of this mixture can be substantially removed by evaporation and crystallization to leave an essentially stoichiometrically equivalent mixture of sodium chlorite and sodium sulfate. These latter two compounds can be recovered together to yield a sodium chlorite product containing sodium sulfate as a diluent.

It will be appreciated that a mixture of chlorites, for example, rather than a single chlorite, could be produced by this invention simply by the use of two or more alkali compounds, or by the use of one alkali compound and the salts of two or more metals. In this way, the necessary metals for the formation of the mixture of chlorites are introduced.

It will be appreciated that the invention as fully exemplified above, can be practiced so that the various components required need not be introduced into the system in any particular sequence so long as they all enter the system to effect the reaction desired.

Although the oxides, hydroxides and carbonates of the alkali metals, the alkaline earth metals and magnesium have been mentioned as the alkali compounds useful for the operation of the invention, the reaction rate is much slower when carbonates are used than it is when oxides or hydroxides are employed. It is for this reason that the oxides and hydroxides are the preferred alkali materials.

In carrying out the process of this invention in the preferred manner, chlorine dioxide, as a dilute gas in the presence of such a diluent as air or nitrogen, is reacted with an aqueous slurry or solution, as the case may be, of the desired alkali materials or the desired salt or salts and the alkali material. This chlorine dioxide is introduced as a dilute gas to prevent the decomposition of the chlorine dioxide. A suitable concentration of chlorine dioxide in the gas phase is about 5% by volume. This concentration depends somewhat upon the temperature employed in the reaction, the lower the temperature, the higher the safe concentration of chlorine dioxide which can be allowed. The temperature of the reaction can be varied from the freezing point to 100° C., a suitable temperature being 50° C. The reaction rate increases with higher temperatures. However, the preferred upper limit is about 70° C.

The quantity of water used for the reacting slurry or solution is not vital to the operation of the invention and may be varied over a wide range. In general, sufficient water should be present at the end of the operation, and before the products are separated, to keep the chlorate and chlorite in solution and thereby prevent their precipitation along with the precipitation of the third compound, providing that it be desired to allow the third compound to be precipitated for removal from the chlorate-chlorite solution. If the invention is to be operated according to the

process exemplified by Equation *b*, wherein only a chlorate and a chlorite are produced, it will be evident that it is only necessary to have sufficient water present to keep these two compounds in solution. However, if potassium chlorate be one of the compounds produced, for example, the amount of water present may be reduced so as to cause the precipitation of some of the potassium chlorate. It further will be realized that should a compound, which it is desired to keep in solution, be inadvertently precipitated, additional water may be added to re-dissolve it.

In general, the amount of water in the reaction vessel wherein chlorine dioxide is being absorbed, should be enough to make the gas-liquid contact efficient. If too thick a slurry is used, difficulty may be experienced in retaining a uniform suspension and in obtaining proper contact between the chlorine dioxide gas and the absorbing medium. Design of the apparatus for the adsorption of chlorine dioxide will dictate to a large degree the optimum thickness of slurry and, therefore, the quantity of water to be used. For most purposes, a suitable concentration of reactants is about 15% by weight in the water slurry or solution. This quantity of water, for example, will keep all of the potassium chlorate of a solution containing equal moles of potassium chlorate and sodium chlorite in solution at 25° C.

After the reaction has been completed, the mixture of final products is removed from the reactor for further treatment to separate the desired products. Inasmuch as the reactants and the products have been selected, as previously described, because of their mutually different solubilities in any given system, the separation of the various products will entail the use of such common chemical engineering unit operations as evaporation, crystallization, washing and filtration.

Related subject matter is disclosed in applicant's copending application, Serial No. 659,403, filed April 2, 1946, which is directed to that specific embodiment in which chlorine dioxide and a single base are substantially completely reacted, and thereafter without separation of the reaction products, a salt is introduced into the system.

Reference is here made also to applicant's copending applications, Serial Nos. 736,113, filed April 20, 1947, and 756,542, 756,543, 756,544, filed June 23, 1947, which applications are directed to processes for the separation of various specific products which may be produced by the process of this application or the process of application 659,043.

This invention can be illustrated further and explained by the following examples:

Example I

A slurry comprising 37 parts of calcium hydroxide, and 43.5 parts of potassium sulfate in 675 parts of water was reacted with 67.5 parts of chlorine dioxide while the slurry was kept at 50° C. Calcium sulfate in the amount of 34 parts precipitated and was removed by filtration. The final filtrate contained 61.2 parts of potassium chlorate and 43.7 parts of calcium chlorite and 684 parts of water.

Example II

A slurry comprising 37 parts of calcium hydroxide, 35.5 parts of sodium sulfate and 43.5 parts of potassium sulfate in 675 parts of water was reacted with 67.5 parts of chlorine dioxide while the slurry was kept at 50° C. Calcium

sulfate in the amount of 68 parts precipitated and was removed by filtration. The final filtrate contained 61.2 parts of potassium chlorate and 45.2 parts of sodium chlorite and 684 parts of water.

Example III

To a slurry of 20.16 parts of magnesium hydroxide, 43.6 parts of potassium sulfate and 27.5 parts of lithium sulfate in 675 parts of water were added 67.5 parts of chlorine dioxide. The resultant substantially neutralized solution then contained 60.2 parts of magnesium sulfate, 61.2 parts of potassium chlorate and 37.2 parts of lithium chlorite in 684 parts of water. These three components were separated from the system by appropriate physical separation methods. The potassium chlorate content was first recovered, followed by a separation of the lithium chlorite and magnesium sulfate.

Example IV

A solution of 56.1 parts of potassium hydroxide and 40 parts of sodium hydroxide in 640 parts of water was reacted with 135 parts of chlorine dioxide, the chlorine dioxide being introduced as a 5% by volume mixture with air. The 122.5 parts of potassium chlorate and the 90.5 parts of sodium chlorite were separated from the thus formed solution by evaporation of the solution to a point at which the solution was saturated with respect to sodium chlorite. About 90% of the potassium chlorate content of the original solution was precipitated at 25° C., filtrated off and dried. The filtrate, containing all of the sodium chlorite and the residual potassium chlorate, was dried to give a solid sodium chlorite product.

Example V

40 A solution saturated with respect to potassium sulfate and containing 80 parts of sodium hydroxide and 87 parts of potassium sulfate was reacted with 135 parts of chlorine dioxide, the chlorine dioxide being in the form of a dilute gas in air, such that the chlorine dioxide concentration was approximately 30 mm. Hg. The 122.5 parts of potassium chlorate in the resultant solution were substantially separated by evaporation and filtration from the 90.5 parts of sodium chlorite and 71 parts of sodium sulfate. The remaining solution of sodium chlorite and sodium sulfate was reduced to a dry product by evaporation. The product thus formed contained about 55% sodium chlorite by weight.

Example VI

To a solution of 80 parts of sodium hydroxide and 77 parts of potassium silicate in 1500 parts of water were added 135 parts chlorine dioxide until the solution was substantially neutral. The 122.5 parts of potassium chlorate formed thereby were removed by evaporation and filtration from the sodium chlorite and sodium silicate also formed. The filtrate from this separation, containing 90.5 parts of sodium chlorite and 61 parts of sodium silicate, was evaporated to dryness to yield a product containing about 59% sodium chlorite by weight.

Example VII

This particular example is illustrated by the accompanying figure to indicate a useful flow sequence for the production of sodium chlorate and calcium chlorite from lime, sodium sulfate, 75 and chlorine dioxide.

A slurry of 74 parts of calcium hydroxide and 71 parts of sodium sulfate in about 1500 parts of water was treated in absorber 1 with 135 parts of chlorine dioxide, the chlorine dioxide being introduced at about 5% concentration in air until the slurry was substantially neutralized. The slurry of products: 68 parts of calcium sulfate, 106.5 parts of sodium chlorate and 87.5 parts of calcium chlorite was filtered in filter 2 to remove the precipitated calcium sulfate. Filtrate from 2, containing the sodium chlorate and calcium chlorite plus a trace of calcium sulfate, was evaporated in evaporator 3 to a concentration sufficient to keep all of the sodium chlorate in solution at 25° C. Considerable calcium chlorite precipitated during the evaporation and was removed in filter 4. The filtrate, now containing sodium chlorate in major quantity, was cooled in crystallizer 5 to cause sodium chlorate to precipitate. Mother liquor from the crystallizer 5, containing the unseparated sodium chlorate and calcium chlorite, was returned to the absorber 1 for recirculation.

What I claim is:

1. A process for producing a chlorate of a metal selected from the group consisting of lithium, sodium, potassium, calcium, barium, strontium and magnesium, and a chlorite of a different metal selected from said group which comprises reacting chlorine dioxide with a compound selected from the class of hydroxides and carbonates, and at least one soluble salt other than a carbonate as an additional reactant, the metals of said compound and said salt being different ones selected from the aforementioned group, said salt being present in approximately half the amount of said compound on a stoichiometrically equivalent basis, said compound and said salt being so selected that the metal of the former reacts with the anion of the latter to form as a third product a salt of relatively different solubility than at least one of the desired products.

2. A process according to claim 1 in which the metal of the chlorate produced is furnished by said salt whereby substantially all of said metal present appears as the chlorate.

3. A process according to claim 1 in which the said third product formed is a relatively insoluble salt.

4. A process for producing a chlorate of a metal selected from the group consisting of lithium, sodium, potassium, calcium, barium, strontium and magnesium and a chlorite of a different metal which comprises reacting chlorine dioxide with a compound selected from the class consisting of hydroxides and carbonates, and as additional reactants two soluble salts other than carbonates, the metals of said compound and said two salts each being different ones selected from the aforementioned group, said two salts each being introduced in approximately half the amount of said compound on a stoichiometrically equivalent basis, said compound and said salts being so selected that the metal of the former reacts with the anions of the latter to form compounds of relatively different solubility than the desired chlorate and chlorite whereby the chlorate of the metal of one salt and the chlorite of the metal of the other salt is produced.

5. A process according to claim 4 in which the said salts have a common anion which combines with the metal of said compound to form a relatively insoluble salt.

6. A process according to claim 4 in which the said salts have a common anion.

7. A process for producing potassium chlorate

and a chlorite of a metal selected from the group consisting of lithium, sodium, calcium, barium, strontium and magnesium, which comprises reacting chlorine dioxide, a compound selected from the class consisting of hydroxides and carbonates, and as an additional reactant at least one soluble salt other than a carbonate, the metals of said compound and said salt each being different ones selected from the group consisting of lithium, sodium, potassium, calcium, barium, strontium and magnesium and one of the metals being potassium, said salt being present in approximately half the amount of said compound on a stoichiometrically equivalent basis, and said compound and said salt being so selected that the metal of the former reacts with the anion of the latter to form as a third product a salt of relatively different solubility than at least one of the desired products.

20 8. A process according to claim 7 in which the potassium is introduced in the form of said soluble salt whereby substantially all of the potassium appears as the chlorate.

9. A process according to claim 7 in which the 25 soluble salt is a potassium salt having an anion which combines with the selected metal of said compound to form a relatively insoluble salt as the third product.

10. A process for producing potassium chlorate 30 and a chlorite of a metal selected from the group consisting of lithium, sodium, calcium, barium, strontium and magnesium, comprising reacting chlorine dioxide, a compound selected from the class consisting of hydroxides and carbonates, and as additional reactants two soluble salts other than carbonates, the metals of said compound and said salts each being different ones selected from the group consisting of lithium, sodium, potassium, calcium, barium, strontium and magnesium, the metal of one of said salts being potassium and the metal of the other salt being that of the desired chlorite, each of said salts being introduced in approximately half the amount of said compound on a stoichiometrically equivalent basis, said compound and said salts being so selected that the metal of the former reacts with the anions of the latter to form additional salt products of relatively different solubility than potassium chlorate and the desired chlorite.

45 11. A process according to claim 10 in which the said two salts have a common anion which combines with the metal of said compound to form a relatively insoluble salt.

12. A process according to claim 10 in which 50 the said two salts have a common anion.

13. A process for producing a chlorate of a metal selected from the group consisting of lithium, sodium, potassium, calcium, barium, strontium and magnesium, and a chlorite of a different metal selected from said group which comprises reacting chlorine dioxide with a compound selected from the class consisting of hydroxides and carbonates, and as a third reactant a soluble salt other than a carbonate, the metals of said compound and said salt being different ones selected from the aforementioned group, said salt being present in approximately half the amount of said compound on a stoichiometrically equivalent basis, said compound and said salt being so selected that the metal of the former reacts with the anion of the latter to form as a third product a salt of relatively different solubility than at least one of the desired products.

70 14. A process according to claim 13 in which 75 potassium chlorate is produced and in which po-

11

tassium is the metal of the salt present as the third reactant.

15. A process for the production of potassium chlorate and calcium chlorite which comprises reacting chlorine dioxide in aqueous medium with calcium hydroxide in the presence of potassium sulfate, said sulfate being present in about half the amount of the hydroxide on a stoichiometrically equivalent basis whereby is formed potassium chlorate, calcium chlorite and calcium sulfate, and separating the chlorate and chlorite from the precipitated calcium sulfate.
